Inventor:

Isaac J. Baxter

United States Patent Office.

ISAAC J. BAXTER, OF PEEKSKILL, NEW YORK.

Design No. 3,001, dated April 21, 1868.

DESIGN FOR A STOVE.

The Schedule referred to in these Letters Patent and making part of the same.

TO ALL WHOM IT MAY CONCERN:

Be it known that I, ISAAC J. BAXTER, of Peekskill, in the county of Westchester, and State of New York, have invented a new and improved Design for Stove; and I do hereby declare that the following is a full, clear, and exact description thereof, which will enable those skilled in the art to make and use the same, reference being had to the accompanying drawings, forming part of this specification, in which—

The drawing represents a perspective view of my invention.

This invention relates to a new design for a six-hole cooking portable range, and consists more particularly in the design for the panels of the stove-doors, and in that for the legs or supports, and in the general stove-design.

A, in the drawings, represents the metallic frame of the stove. B is the door to the fireplace. C is the door to the frying-oven.

The door C is ornamented with a moulding, a, and with an ornamental beaded moulding, b. In the middle is an ornamental centre-piece, c, as shown, which is also arranged in the middle of the door B. The door C is rectangular, while the door B has rounded corners, as shown.

The panels D at the sides of the stove have similar mouldings and centre-pieces as the door C, but the corners of such panels are rounded, as shown.

The faces of the legs E E are decorated with an ornamental relief, as shown.

The plate F, which is set in front of the ash-pan, is perforated with slots, two arranged vertically at the sides, one horizontally in the centre, and two vertically above and below the central horizontal slot respectively, as is clearly shown in the drawing:

I claim as new, and desire to secure by Letters Patent—

The design for stove, as set forth and shown.

ISAAC J. BAXTER.
